ANTIFLOOD DEVICE FOR FLOOR DRAINS

William P. Gaspar, Flint, Mich., assignor to Basement Sentinel Company, Flint, Mich., a corporation of Michigan

Application March 26, 1949, Serial No. 83,663

3 Claims. (Cl. 182—25)

This invention relates in general to an anti-flood device for a floor drain and more particularly to a type thereof having an automatic valve which permits water to back up through said drain into said anti-flood device without inundating the floor therearound.

There are many conditions, such as spring thaws or a congested sewage system, which may cause water to back up through a floor drain and flood the surrounding floor, thereby damaging property and endangering health. In order to overcome this situation a valve is installed in said floor drain. Presently known types of valve mechanisms for automatically closing said floor drain have been found unreliable in operation and extremely difficult to clean or service.

The only known types of automatic back-flood valves are for below-floor installation. Accordingly, when the flood level in the sewer rises substantially above the level of the floor, the upward hydrostatic pressure against the closed drain becomes sufficient to loosen the drain from the surrounding floor or create leaks around said drain by cracking the floor.

Accordingly, a primary object of this invention is the provision of an anti-flood device for a floor drain which permits water to back up through the drain without inundating the floor therearound, and which can be easily and quickly installed in, or removed from, said drain.

A further object of this invention is the provision of a device, as aforesaid, which will not cause said drain to be disengaged from the surrounding floor due to upward hydrostatic pressure during flood conditions.

A further object of this invention is the provision of a device, as aforesaid, which is easy to clean and service and which is positive in action and reliable in operation.

Other objects and purposes of this invention will become apparent to persons familiar with this type of equipment upon referring to the accompanying drawings and upon reading the following specification.

In meeting those objects and purposes heretofore mentioned, as well as others incidental thereto and associated therewith, I have provided a drain plate which rests on, and is secured to, the floor around a drain hole and has a circular threaded opening in the center thereof. A cylindrical valve housing is threadedly supported, in an axially vertical position, within said threaded opening in the drain plate and extends down into said drain hole. A drain port is provided in the side wall of said housing just above said

39 drain plate to allow said drain port to be connected to a sewer line 40 which passes through the ground 41 under the basement floor 42. The housing 43 is secured to the drain plate 44 and has a drain port 45 which is 46

47 connected to a stand pipe 48 which passes through the ground 49 under the basement floor 50. The stand pipe 51 is secured to the housing 52 and has a drain port 53 which is 54

55 connected to a sewer 56 by means of a waste pipe 57 which passes through the ground 58 under the basement floor 59. The waste pipe 60 is secured to the housing 61 and has a drain port 62 which is 63

64 connected to a stand pipe 65 which passes through the ground 66 under the basement floor 67. The stand pipe 68 is secured to the housing 69 and has a drain port 70 which is 71

72 connected to a sewer 73 by means of a waste pipe 74 which passes through the ground 75 under the basement floor 76. The waste pipe 77 is secured to the housing 78 and has a drain port 79 which is 80

81 connected to a stand pipe 82 which passes through the ground 83 under the basement floor 84. The stand pipe 85 is secured to the housing 86 and has a drain port 87 which is 88

2

89 drain plate and a valve is provided within said housing which closes said drain port, when water rises within said housing, before the water reaches said port. A stand pipe may be secured in a vertical position to the upper end of said housing permitting water to back up through said housing and seek its level within said stand pipe.

For illustrations of a preferred embodiment 10 of the invention, attention is directed to the accompanying drawings in which:

Figure 1 is a vertical cross-sectional view of a basement showing a floor drain equipped with my anti-flood device.

Figure 2 is a cross-sectional view of Figure 1, about as taken along the line II—II, with the automatic valve in closed position.

Figure 3 is a cross-sectional view of the valve housing, about as taken along the line II—II in Figure 1, with the valve in the open position.

Construction

The anti-flood device 10 (Figures 1 and 2), to which this invention relates, is herein disclosed, 25 for illustrative purposes only, as applied to use with a drain hole 11 in a basement floor 12. However, it will be recognized from the description that said anti-flood device may be used in connection with any floor drain. The drain hole 11, for the purposes of illustration, is connected to a sewer 13 by means of the waste pipe 14 which passes through the ground 15 under the basement floor 12 in a conventional manner.

For the purpose of convenience in description, 30 the terms "upper" or "upwardly" and "lower" or "downwardly," as used in the following specification, will be understood to refer to the anti-flood device 10 and parts cooperating therewith when positioned and/or operating in their normal manner of use. The terms "inwardly" and "outwardly" shall be understood to mean toward and away, respectively, from the geometric center of the device.

The anti-flood device 10 (Figure 2) is comprised of a substantially cylindrical valve housing 17, which is supportable upon a circular substantially dish-shaped drain plate 16 and a hollow stand pipe 18 which is securable to said housing. The housing, drain plate and stand pipe are all 45 preferably made from a rust resistant material such as brass. The drain plate 16, which has a circular opening 19 preferably coaxial with the circular periphery 21 thereof, advantageously slopes downwardly from said periphery toward said opening 19, thereby having the shape of a

frustum of an inverted cone. The walls of the circular opening 19 are preferably extended downwardly to provide the cylindrical extension 22 which is internally threaded.

The drain plate 16, which is preferably set in concrete 23 surrounding the drain hole 11 for permanent attachment to the floor 12, is preferably disposed substantially horizontally and its outer periphery 21 is preferably slightly lower than the upper surface 24 of said basement floor.

The cylindrical valve housing 17 (Figure 3) is provided with a substantially coaxial valve chamber 25 which extends through the entire length thereof, and opens out of both axial ends thereof. The said chamber 25 is preferably, but not necessarily, provided with an enlarged portion 26 near the upper end thereof, which portion is provided with a circular drain port 27 through the side wall of the housing 17.

The valve housing 17 is externally threaded immediately below the enlarged portion 26 for cooperation with the internally threaded cylindrical extension 22 of the drain plate 16. Accordingly, the drain port 27 is immediately above the upper surface of the drain plate 16 when the valve housing 17 is threadedly secured thereto, and said valve housing is, accordingly, in an axially vertical position. The lower end of the valve housing 17, which extends down into the drain hole 11, is provided with an inner screen 28 which extends completely across the valve chamber 25 near the lower end thereof. The housing side wall surrounding the upper end of the valve chamber 25 is internally threaded for cooperation with the lower, externally threaded end 29 of the hollow stand pipe 18, which pipe is preferably substantially coaxial with the valve housing 17 and removable therefrom.

A valve head 31, which may be of any convenient, conventional type, is here shown as having a circular disk 32 secured to a valve arm 33, which arm is hinged supported upon the valve housing side wall within the chamber enlarged portion 26 directly above the drain port 27. The valve arm 33 is preferably so positioned that the circular disk 32 closes the drain port 27 when said disk lies substantially within a vertical plane.

The lower end of the valve arm 33 is pivotally engaged by one end of a hinged float support bar 34. The opposite end of said float bar 34 is pivotally supported upon that side of the wall of the chamber enlarged portion 26 remote from the drain port 27. The hinge point 35 in the support bar 34 is preferably about midway between the extremities of said bar, which bar is preferably slightly longer than the distance between the said pivot points on the wall of the chamber enlarged portion 26 and the lower end of the valve arm 33.

The float bar 34 is preferably assembled so that as the ends thereof are moved toward or away from each other, the hinge point 35 will move upwardly and downwardly, respectively, substantially below the level of the said ends of the bar. Accordingly, upward movement of the hinge point 35 will cause the support bar 34 to close the valve head 31 over the drain port 27 before the said support bar 34 can be straightened out and, therefore, before the hinge point 35 can be raised above the level of the ends of said bar.

A buoyant float 36 of any convenient, conventional type is secured to, and suspended from, the float support bar 34 at the hinge point 35 thereof

within the lower end of the valve chamber 25. Normally, the weight of the float 36 tends to pull the hinge point downwardly, thereby holding the valve head 31 in the open position, as shown in Figure 3.

An outer screen 37, supportable upon the plate periphery 21, may be provided around the valve housing 17 to prevent undesirable material from entering the drain port 27.

10

Operation

The circular drain plate 16, which is preferably substantially as hereinabove described, may be permanently installed in the floor, such as a basement floor 12 (Figure 2), by means such as concrete 23 so that a substantially circular drain hole 11 is provided between the cylindrical extension 22 of said drain plate 16 and the upper edge of the waste pipe 14. The drain plate 16 is preferably substantially horizontal and the cylindrical extension 22 is preferably lower than the plate outer periphery 21 so that said drain plate slopes downwardly from said periphery 21 toward the circular opening 19.

The cylindrical valve housing 17, complete with the valve mechanism inside thereof, the inside screen 28, and the outside screen 37, may be inserted into the circular opening 19 and threadedly engaged by the internal threads of said cylindrical extension 22, thereby being disposed in a vertical position. The drain port 27 will, therefore, be immediately above the upper surface of the drain plate 16, and any water or other fluids flowing into the drain plate 16 may pass through the drain port 27, the valve chamber 25, the drain hole 11, and out the waste pipe 14. Under these circumstances, the valve head 31 will be in the open position as shown in Figure 3.

The stand pipe lower threaded end 29 is threadedly secured to the upper end of the valve housing 17 and is preferably of such length that it will permit water backing up through the waste pipe 14 and drain hole 11 to seek its level therein under the most extreme conditions which may be anticipated.

If and when the sewer 13 should in any way cause the liquid therewithin to back up the waste pipe 14 and through the drain hole 11, the anti-flood device 40 in the position hereinabove described, will positively prevent the inundation of the basement floor 12. As the water backs up through the waste pipe 14 and through the chamber 25, it raises the float 36 and thereby urges the pivoted ends of the float support bar 34 away from each other. Since the one end of the float bar 34 is secured to the side of the valve chamber 25, the opposite end of said float bar, which is pivotally connected to the valve head 31, tends to close said valve head over the drain port 27 as the float 36 rises. The drain port 27 will be completely and satisfactorily closed by the valve head 31 well before the water rising through the valve housing 17 can reach the level of the said valve head 31. Thus, the water will bypass the drain port 27 as it rises through the valve housing and continues to seek its level up through the stand pipe 18. The buoyancy of the float 36 will continue to keep the valve head 31 closed over the drain port 27 until the level of the water recedes below the level of the float 36 at which time the valve head 31 will again be pivoted away from closed position over the drain port 27.

Inasmuch as the cylindrical valve housing 17 and the parts associated therewith may be re-

moved from the drain plate 16 very simply and very quickly, it takes very little effort to keep said parts clean and ready for immediate and positive operation.

At times when back flooding through the waste pipe is very unlikely, the valve housing 17 and associated parts may be removed from the drain plate 16 entirely, or, if desired, the stand pipe 18 may be removed from the valve housing 17 and replaced by a solid plug, not shown. If the valve housing 17 is completely removed from the drain plate 16, a circular drain cover of any convenient type, not shown, may be placed over the drain plate 16. In such a case, the anti-flood device 10 could be kept in a handy place for immediate installation in the drain plate 16 when needed.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claims.

I claim:

1. In an anti-flood device for a floor drain, the combination comprising: a circular, dish-shaped drain plate, having a coaxial, circular opening whose walls are threaded and substantially lower than the periphery of said plate; a cylindrical valve housing having an externally threaded portion intermediate its axial ends for cooperation with the threaded walls of said circular opening, said housing being axially vertically disposed within said opening and having a coaxial cylindrical chamber extending therethrough, the walls of said chamber being internally threaded near the upper end thereof; a stand pipe externally threaded near one end for cooperation with the internally threaded upper end of said housing and a screen across said chamber adjacent to the lower end thereof; a screen surrounding that portion of said housing extending above said drain plate and resting upon the outer edge of said plate; a circular drain port through the side wall of said chamber above said threaded portion; a valve head pivotally supported at its upper edge within said chamber upon said side wall above said drain port for closing same; a bar within said chamber having a hinge point intermediate its ends, one end of said bar being pivotally secured to the lower edge of said valve head and the other end being pivotally secured to the wall of said chamber opposite said drain port; and a buoyant float secured

to and suspended from said hinge point of said bar within the lower end of said valve housing; whereby water rising within said valve housing raises said float, thereby causing said valve to close said port, and seeks its level within said stand pipe.

5 2. In an anti-flood device for a floor drain, the combination comprising: a substantially dish-shaped, circular drain plate having a coaxial, circular opening therethrough; a cylindrical, vertically disposed valve housing removably and coaxially supported, intermediate its axial ends, within said opening and upon said plate, said housing having a coaxial cylindrical chamber extending therethrough; a stand pipe communicating with said chamber at the upper end of said housing and a screen across the lower end of said chamber; a drain port through the side wall of said chamber above said drain plate and a valve head hingedly supported within said chamber adjacent to said drain port for closing same; hinged linkage extending between and pivotally secured to said valve head and said side wall; and a float suspended from said linkage within the lower end of said chamber, whereby water rising within said housing raises said float, thereby causing said valve head to close said port before said water reaches it and permitting said water to rise in said stand pipe.

20 3. In an anti-flood device for a floor drain, the combination comprising: a substantially dish-shaped, circular drain plate having a circular opening therethrough; a cylindrical, substantially vertical valve housing removably supported within said circular opening, said housing having a coaxial, cylindrical chamber extending therethrough; a vertical stand pipe communicating with the upper end of said chamber; a drain port through the side wall of said chamber above said drain plate and a valve head hingedly supported within said chamber for closing said port; a float within the lower end of said housing and linkage connecting said float to said valve head, whereby upward movement of said float causes said valve head to close said drain port.
